UNITED STATES PATENT OFFICE

CHARLES C. BOLEN, OF MARION, OHIO

RAILWAY BRAKE

Application filed May 18, 1931. Serial No. 538,047.

This invention relates to operating mechanism for hand brakes for use in connection with railway cars, street cars and other similar vehicles.

5 It is the object of this invention to provide a very simple and highly efficient hand-operated mechanism for applying brakes to car wheels.

It is particularly the object of this invention to provide a hand-operated brake mechanism in which there is a drum operated by a longitudinally adjustable lever, adapted to have an operating position and an idle position in which the handle is supported so that 15 it cannot be moved longitudinally.

It is a further object of this invention to provide, in connection with a hand-operated brake mechanism, means for rapid operation of a drum around which a chain is coiled for 20 taking up slack in the chain.

It is also an object of this invention to provide a pawl and ratchet mechanism for holding the chain-carrying drum in braking position, and which may be released so that the 25 drum may rotate to let off the chain.

These and other advantages will appear from the following description taken in connection with the drawings.

Referring to the drawings:

30 Figure 1 is an end elevation of a railway car with the present braking apparatus attached thereto.

Figure 2 is a front elevation of the braking apparatus detached from the car.

35 Figure 3 is a section on the line 3—3 of Figure 2.

Figure 4 is a section on the line 4—4 of Figure 2.

Figure 5 is a view on the line 5—5 of Figure 2.

Figure 6 is a section on the line 6—6 of Figure 2.

Figure 7 is a section on the line 7—7 of Figure 2.

45 Figure 8 is a view showing the end of the lever and the operating ratchet wheel engaged by the lever.

The present brake operating apparatus is adapted to be used in connection with cars of various kinds, one of which is indicated

by the numeral 1, in Figure 1, and supported on wheels 2. In this figure the braking apparatus is shown attached to the rear end of a coal car, but it may be attached to other types of cars and to other parts rather than the end.

55 This apparatus is supported on the car by means of a frame 3, which has extending therefrom substantially parallel arms 4. These arms have extending laterally therefrom ears 5, by which the frame is attached to the car by means of bolts passing through holes 6. Adjacent each ear and attached to each arm is a boss 7, which serves as a support for a spindle on one end of a drum 8. Each end of the drum is reduced in size to 60 form the spindle, which fits in bearings in the bosses 7. The drum has around the periphery thereof a spiral groove 9, which forms a seat for a brake operating chain 11, one end of which is attached to the drum by means of 65 lugs 10. These lugs are at one end of the drum so that as the drum is rotated the chain is wound on the drum and seated in the spiral groove 9. By means of this groove the chain is coiled around the drum from one end 70 to the other in the groove.

75 At one end of the drum and adjacent the spindle on that end is a ratchet wheel 12 for rotating the drum. Mounted on the spindle of the drum, adjacent the ratchet wheel 12, is a handle member 13 which has a slot 14 therein in which the spindle is located. By means of the slot 14 the handle is permitted to have a certain limited amount of longitudinal movement with relation to the ratchet wheel and the drum. The ratchet wheel has teeth on the periphery thereof which are engaged for the rotation of the drum by teeth 16 on a projection 15 of the handle. This projection in the present instance is shown to have two teeth. Other numbers of teeth may be used.

80 These teeth are so located with respect to the handle and the drum that when the handle is in one position on the spindle these teeth engage the ratchet teeth for rotating the drum, and when the handle is in another position on the spindle the teeth are out of engagement with the teeth of the ratchet wheel.

85 90 95 100

so that the drum may rotate free of the teeth on the handle.

In order to support the handle in a substantially fixed vertical position there is provided on the handle a stop 17 for engagement with a stop member 18 on one arm. Adjacent the stop 17 is a cam surface 18a. By means of the stops the handle is supported against swinging and in a substantially fixed position, and by means of the cam surface 18a the handle is held in position so that the teeth of the handle are out of engagement with the teeth of the ratchet wheel and cannot engage the teeth of the ratchet wheel until the handle has been swung sufficiently to clear the cam surface for longitudinal movement to bring the teeth of the handle in engagement with the teeth of the ratchet wheel. After the respective teeth have engaged each other the movement of the handle will cause the drum to rotate. For the purpose of preventing back rotation of the drum there is provided, adjacent the ratchet wheel 12, a second ratchet wheel 19. Both of these ratchet wheels are fixed to the drum and control the rotation of the drum.

Located on top of the frame are bearings 20, which have extending therethrough a shaft 21 supporting a pawl 22 for engagement with the ratchet wheel 19 to prevent the drum from rotating backwardly when the handle is moved for a new engagement with the ratchet wheel 12. The pawl may be swung from ratchet wheel engaging position to a free position so that the drum may be easily rotated without interference by the pawl 22.

For the purpose of holding the pawl either in engagement with the ratchet wheel 19 or free from engagement with the wheel, a weight 23 is provided. The weight and pawl are both pivotally mounted on the shaft 21, and have a limited amount of movement with respect to each other. The weight engages two shoulders 24 on the pawl, one for holding the pawl against the ratchet wheel and the other for tipping it and holding it out of contact with the ratchet wheel.

On the other end of the drum from the two ratchet wheels 12 and 19 is a ratchet wheel 25 for quick operation for the purpose of taking up slack in the chain. This ratchet wheel is constructed in the same manner that the others are. This wheel is operated by means of a longitudinally movable hand lever or bar 27, which has at one end a hand hold loop 28. This bar is supported on the frame by means of a bolt 26, which passes through a slot 29 in the operating bar 27. On one edge of the bar is a set of teeth 30 for engagement with the teeth of the ratchet wheel for quick rotation of the drum. The relative position of the ratchet wheel 25 and the bar 27 is shown in Figure 4.

When it is desired to rotate the drum

through the ratchet wheel 25 and the bar 27 is moved upwardly, as shown in Figure 4, so that its teeth 30 engage the teeth of the ratchet wheel, thereby rotating the ratchet wheel and drum in anti-clockwise direction. This operation of the drum is for the purpose of taking up slack in the chain 11. If the lever 13 were used solely for rotating the drum the operation of the drum would be so slow that time would be lost, so that in order to save and economize time rapid means is provided for rotating the drum to take up the slack in the chain. After the slack has been taken up the drum is further rotated for braking purposes by operating the handle 13.

For the purpose of transporting the frame and the whole brake operating mechanism, or for supporting the operator while operating the mechanism, there is provided on the frame a handle 31 which may also be used as a hand hold while the take-up mechanism is being operated. As shown in Figure 1 the chain 11 extends downwardly and over a pulley 32 located beneath one end of the car. From this pulley the chain extends to a braking apparatus under the car, not shown.

Operation

Under ordinary conditions the chain 11 has a certain degree of slack therein. In order to take up this slack without undue loss of time there is provided, in connection with the ratchet wheel on one end of the drum, a longitudinally movable toothed lever having teeth to engage the ratchet wheel for quick rotation. This lever is either pushed or pulled longitudinally, with its teeth engaging the teeth of the ratchet wheel, thereby rotating the drum rapidly for taking up slack in the chain. During this operation the holding pawl is preventing back rotation of the drum.

After the slack has been taken up from the chain the drum is further operated by a movement of the lever 13. When it is desired to rotate the drum the lever is pushed longitudinally so that its teeth 16 engage the teeth on the ratchet wheel 12. When these teeth thus engage an operation of the handle will cause the drum to rotate. When the handle has been moved as far as possible in the rotation of the drum it is again shifted longitudinally toward the operator and moved to original position. The lever is again moved longitudinally so that the teeth on the handle and the ratchet can engage each other for a further operation of the drum.

In Figures 5 and 6 the handle is shown in normal idle, or what might be called first position. In this position the projection 17 engages the lug or stop 18 and the cam surface 18a. When the handle is in this position the cam surface prevents a longitudinal movement thereof. In order to operate the

lever, as shown in Figures 5 and 6, it must be swung clockwise. This swinging must take place before the lever can be moved longitudinally so its teeth can engage the teeth of the ratchet wheel. When the lever has been swung so that it does not engage the cam surface 18a it can be pushed longitudinally so that its teeth will engage the teeth on the ratchet wheel, and thereby a further movement of the lever in a clockwise direction will cause the ratchet wheel and the drum to rotate, as shown in these two Figures 5 and 6.

It will be noticed that the spindle is in the upper end of the slot 14 in the end of the handle. In Figure 8 the relative position of the handle with respect to the ratchet wheel is shown, after the ratchet wheel has been engaged by the handle. This figure shows the spindle in the lower end of the slot in the handle, and it shows the teeth on the lever in engagement with the teeth of the ratchet wheel. A movement of the handle in anti-clockwise direction, as shown in Figure 8, causes the ratchet wheel and the drum to rotate for braking purposes. When the handle is in the position shown in Figure 8 it is free from the stop 18 and the cam surface 18a; otherwise, the teeth of the handle could not engage the teeth of the ratchet wheel.

I desire to comprehend within my invention such modifications as may be embraced within my claims and the scope of my invention.

Having thus fully described my invention, what I claim as new and desire to secure by Letters Patent, is:

1. In a brake operating attachment, a frame having thereon a hand hold, a drum on the frame adapted on rotation to take up the brake, said hand hold being located above the drum and a pawl on the frame adjacent the hand hold to hold the drum against rotation and releasing the brake, said pawl having an extension thereon so located relative to the hand hold whereby the extension may be engaged by the thumb of the hand on the hand hold to release the pawl from the drum.

2. In a brake mechanism, a frame, a drum having a ratchet wheel thereon rotatably supported by the frame, a chain on the drum having one end connected to suitable braking mechanism, a swingable bar having a longitudinally extending slot therein and ratchet teeth on one edge, a support on the frame adjacent the periphery of the ratchet wheel extending into the slot for supporting and guiding the bar so that the bar may be swung and moved longitudinally back and forth for operating the ratchet wheel, said supporting means being located to support the bar in substantially vertical position with the bar teeth out of engagement with the

ratchet wheel, and means to hold the drum against rotation when the bar is out of engagement with the ratchet wheel.

3. The combination of a drum and chain to be operated thereby, said chain being adapted to be slack a part of the time and taut at other times, said drum having a plurality of ratchet devices; a slideable and swingable bar having ratchet teeth and a support for the bar for holding the same in substantially vertical position with the teeth of the bar out of engagement with the teeth of one of said ratchet devices and adapted to be swung to engage said teeth upon an upward pull of the bar and to be disengaged upon downward movement of the bar to quickly take up the slack in the chain, and a hand lever adapted to operate the other ratchet device to rotate the drum slowly and with increased power after the slack is taken out of the chain.

In testimony whereof, I affix my signature.
CHARLES C. BOLEN.
